UNITED STATES PATENT OFFICE.

PHILIP H. RINN, OF SAN FRANCISCO, CALIFORNIA, ASSIGNOR TO THE CALIFORNIA JEWELRY COMPANY, OF SAME PLACE.

DESIGN FOR A BADGE OR EMBLEM.

SPECIFICATION forming part of Design No. 13,992, dated June 19, 1883.

Application filed May 3, 1883. Term of patent 3½ years.

To all whom it may concern:

Be it known that I, PHILIP H. RINN, a citizen of the United States, residing at San Francisco, county of San Francisco, State of California, have invented and produced a new and original Design for a Badge or Emblem, of which the following is a specification.

My invention relates to a novel design for pins, badges, or emblems which are made in the form of a Maltese cross; and it consists of a mosaic or inlaid work of squares upon the arms of the cross, so as to imitate a tessellated pavement in perspective, as will be more fully explained by reference to the accompanying drawing, in which the figure is a view of one side of my device.

A is a Knights Templar jewel or emblem, having the usual inscriptions in the center and the four arms B diverging in the usual manner, as shown.

The leading feature of my design is the inlaying of the arms of the cross with the representation of tessellated pavements in contrasting colors.

sentation of tessellated pavements in contrasting colors.

The lines of division between the squares 25 may be made as shown in the present case, one series being drawn parallel with the outer edges of the arms, while the other series are drawn radially from the margin of the outer circle of the center to the outer edges. 30

Having thus described my invention, what I claim as new, and desire to secure by Letters Patent, is—

The herein-set-forth design for a badge or emblem, consisting, essentially, of a Maltese 35 cross having on its arms the representation of tessellated pavement in contrasting colors, as described and shown.

In witness whereof I hereunto set my hand.

PHILIP HENRY RINN.
